UNITED STATES PATENT OFFICE.

ROBERT L. CAMPBELL, OF CHICAGO, ILLINOIS.

LAST.

SPECIFICATION forming part of Letters Patent No. 337,131, dated March 2, 1886.

Application filed September 10, 1885. Serial No. 176,662. (No model.)

To all whom it may concern:

Be it known that I, ROBERT L. CAMPBELL, of Chicago, in the county of Cook and State of Illinois, have invented certain new and useful 5 Improvements in Lasts; and I do hereby declare that the following is a full, clear, and exact description thereof, reference being had to the accompanying drawings, and to the letters of reference marked thereon, which form a 10 part of this specification.

This invention relates to the construction of the metal thimble and plate which are applied to wooden lasts intended to be used with jacks in the manufacture of shoes thereon; and the 15 object of the invention is to provide such a construction as will more perfectly prevent the last from splitting. The "metals" referred to comprise a thimble let into a hole in the cone of the last and a strap secured to the last 20 and surrounding the hole which receives the thimble. The thimble is intended to receive the stud which projects from the upper end of the heel-post of the jack, and which holds the last by being clamped in said thimble by the 25 familiar movement of the ball-post of the jack. In this operation of the jack, and under the heavy hammering to which the last is subjected when on the jack, there is a tendency to loosen the metals and to split the last, which is only 30 partially remedied by the construction of the metals referred to, as heretofore made and applied.

My improvement consists in connecting these two metals, whereby each is in part supported 35 from the other, and in substituting for the strap a top plate made concave upon its under surface and fitted to a correspondingly-shaped seat upon the last, so that both together better keep in place and serve to more effectually prevent the last from splitting in use. Two forms of 40 my invention are shown for this purpose, one consisting in an arrangement of the top plate or strap around the outer end of the thimble, and the other in making the strap or plate integral with the thimble.

In the drawings, Figure 1 is a perspective view of a last provided with one form of my improvement. Fig. 2 is a transverse vertical section of the last taken centrally through the 45 thimble and plate. Fig. 3 is a perspective view of the plate and thimble made integral with each other. Fig. 4 is a perspective view

of the wooden portion of the last bored and recessed to proper shape to receive the combined plate and thimble. Fig. 5 is a transverse vertical section through the plate and thimble of Fig. 4, showing the metal parts in place.

A is a wooden last, B is the thimble, and C is the plate or strap, the latter being let into the cone of the last flush with the wood, and the thimble being driven closely into the hole a, bored in the cone of the last to receive it. Said plate C is inclined downwardly and outwardly on its under surface from the center line of the last, and the wood of the last is correspondingly shaped, so as to fit the concaved under face of the said plate C.

In the construction shown in Figs. 1 and 2 the thimble B is extended through the plate C, the hole in the latter being made of size to receive the end of the thimble at a tight fit, so that lateral strain applied to the thimble by the stud on the heel-post of the jack is met, not only by the bearing of the thimble in its wooden socket, but also by its bearing against the plate C. This plate being let into the wood flush with the latter, so as to bear upon the shoulders c and held by screws or nails, serves materially to aid in the support of the thimble and to prevent any movement thereof calculated to displace it or to split the wood. On the other hand, the engagement of the plate with the thimble, which is supported by the walls of the hole a, prevents the loosening of the plate C. In short, both the thimble B and the plate C thus co-operate to sustain each other and to prevent each other from being loosened and the last from splitting as a result of their becoming loose, which frequently happens in the older construction described.

The thimble and plate in Figs. 1 and 2 are represented as being of wrought-iron, and as being engaged with each other only by the insertion of the upper end of the thimble through the plate; but, if desired, the thimble and plate may be welded or brazed to each other, so as to form a single piece.

In Figs. 3 and 5 the thimble and plate are shown to be made in a single piece, as when they are of malleable iron.

The object and effect of the construction above described, wherein the plate C is made concave upon its under surface, is that when

the plate is fastened upon the last it will laterally confine the wood, as intended by one old form of strap well known, which not only reaches across the top of the last, as shown in Figs. 1 and 2, but also reaches down the sides of the last. In this old construction, however, the strap, being made of wrought strap-iron, has little effect to actually clamp the last laterally, and the latter therefore easily splits, notwithstanding its presence. In said old construction, moreover, constant hammering serves to loosen and start the laterally-inserted screws of the plate, so that their projecting heads frequently tear the linings of the shoes. The plate C of Figs. 3 and 5 is made so thick as to have greater strength than this old wrought-iron strap, and by its rigidity and concaved form of its under surface, described, firmly clamps the last with the result, as stated, of preventing the latter from splitting. Vertical screws may be inserted through this plate, as

through the plate of Figs. 1 and 2, or the plate and thimble may both be held in place in the construction of Figs. 3 and 5 by the closeness with which the thimble enters the hole *a* of the wood. 25

I claim as my invention—

The combination, with a last, A, having a hole, *a*, and recess *a'*, the bottom of which recess is downwardly and outwardly inclined laterally from the middle, of a cast thimble 30 and plate, B C, the under surfaces of said plate being downwardly and outwardly inclined to fit the bottom of the recess *a'*, substantially as and for the purpose set forth. 35

In testimony that I claim the foregoing as my invention I affix my signature in presence of two witnesses.

ROBERT L. CAMPBELL.
